UNITED STATES PATENT OFFICE.

JULIUS SAMACH, OF NEW YORK, N. Y., ASSIGNOR TO ENTERPRISE ELECTRIC NOVELTY CO., INC., OF NEW YORK, N. Y., A CORPORATION OF NEW YORK.

PORTABLE FLASH-LIGHT.

1,260,067.

Specification of Letters Patent. Patented Mar. 19, 1918.

Application filed June 30, 1917. Serial No. 177,928.

To all whom it may concern:

Be it known that I, JULIUS SAMACH, a citizen of the United States, and resident of New York city, in the county of New York and State of New York, have invented certain new and useful Improvements in Portable Flash-Lights, of which the following is a specification.

The invention relates in general to an improvement in electric portable flash lights and particularly relates to a mounting for holding in place a well known commercial article which forms a single unit including a reflector and a light therefor.

10 One of the objects of the invention is to simplify the usual types of such mountings and to provide a non-short circuiting holder for the reflector and associated parts. I attain this invention by designing a simple 15 readily removable insert for the containing casing which insert will provide in the one article a means for insulating the reflector from the casing, a means for securely holding the reflector in position insulated from 20 the casing to prevent accidental short circuiting and a means for providing an electric terminal connected electrically to the lamp and constituting the coacting element of a controlling circuit closer.

25 Specifically the insert is in the form of a disk of insulating material shaped to fit the metallic containing casing and which is provided with an opening outlined by a metallic ring spaced from the casing and designed 30 to have the reflector fit therein. The ring is so mounted in the containing casing that it is disposed in the path of the movable element of the circuit closer thus eliminating 35 the necessity of providing a separate contact 40 for the movable element of the usual circuit closer used with such devices.

Various other objects and advantages of the invention will be in part obvious from an inspection of the accompanying drawings and in part will be more fully set forth in the following particular description of one form of mechanism embodying my invention, and the invention also consists in certain new and novel features of construction and combination of parts hereinafter set forth and claimed.

Referring to the accompanying drawings: Figure 1 is a side view of a flash light

with the forward end broken away to show a preferred embodiment of my invention installed therein;

Fig. 2 is a perspective view of the mounting disk shown in Fig. 1; and

Figs. 3 and 4 are transverse sectional views showing slightly modified forms of the reflector holding rings.

In the following description and in the claims, parts will be identified by specific names for convenience of expression but they are intended to be as generic in their application to similar parts as the art will permit.

In the drawings there is shown a metallic containing casing 10 containing a battery 11 to supply current to a lamp 12 carried by a metallic reflector 13. It is understood that this funnel shaped reflector with the socket of the lamp screwed into its small end is a well known article of commerce used in connection with flash lights. The casing is provided interiorly with a groove 14 adjacent its forward end, which end is screw threaded as shown at 15 to receive a retaining ring 16 designed to hold the lens 17 in place on the casing and in engagement with the open end 18 of the reflector as is used in one form of such flash lights.

A disk 19 of insulating material, such as compressed paper composition, is fitted within the groove 14 by springing the same in place. The disk is provided with a centrally disposed opening outlined by a metallic ring 20, having a flat rear face 21 fastened to the disk by rivets 22. In some forms of the device this ring is spun to provide a frusto-conical seat 23 constituting a bowl shaped abutment to receive the small end of the reflector 13 while permitting the lamp base and its socket 24 to pass therethrough to contact with the battery 11. In the form shown in Fig. 3 a plate 20' may be positioned on the front of the disk 19 to contact with and center the reflector or, in the form shown in Fig. 4, the reflector may be seated in the edge 27 of the cup 28.

The rear face 21 of this metallic ring constitutes the fixed contact member of a circuit closer, the movable member of which is in the form of a metallic strip 25 actuated exteriorly of the casing by a sliding finger piece 26. The strip 25 has an indent end 27 constituting a flexible contact designed to

engage face 21 and protected by the disk insert even when the reflector and lamp unit is demounted from the casing.

In order to assemble the reflector and lamp unit in the casing the disk is inserted through the open front end of the casing and sprung into the groove or if there be no groove dependence is placed upon the frictional tight fit of the disk against the inner wall of the casing. The rear end of the reflector is positioned within the hole in the metallic ring, the lens placed in the retaining ring and this ring is then screwed into place. The lens bearing on the forward end of the reflector centers the same within the disk and coacts therewith to insulate the reflector from the metallic casing.

Moving the finger piece to the left as shown in Fig. 1 causes the movable element 20 of the circuit closer to contact with the rear side of the metal ring thus completing the circuit from the battery through the ring, reflector and lamp back to the battery.

By means of a device of this character, the usual complicated mountings for the reflector unit is eliminated and a simple disk performs all the functions of the several parts found in the old types of mountings.

These disks use the least possible amount 30 of material and need have a rigidity merely sufficient to hold the reflector centered in place. The disks can be readily stamped to shape and the metallic ring inserted by a simple die press operation, thus permitting 35 the machining of these disks cheaply in large numbers. There is a further saving in the labor cost of assembling the parts for it is merely necessary to press the disks into position in the grooves.

40 Further it is apparent that this device constitutes a double safe guard against short circuiting in that it is self insulated, and provides a seat for holding the reflector securely in position and out of electric contact with the metallic casing.

While I have shown and described, and have pointed out in the annexed claims, certain novel features of my invention, it will be understood that various omissions, substitutions and changes in the form and details 50 of the device illustrated and in its operation may be made by those skilled in the art without departing from the spirit of the invention.

55 Having thus described my invention, I claim:

1. In a flash light, the combination with a metallic casing provided with a groove on the inside thereof, of a disk fitted in said

groove, a metallic reflector seat carried centrally by said disk and insulated from said casing, a metallic reflector fitted to said seat to support the same, a lamp connected electrically to said reflector, and circuit closing means adapted to engage said seat to complete the circuit through the lamp. 60 65

2. In a flash light, the combination with a metallic casing, a disk of insulating material fitted in said casing, a metallic reflector seat carried by said disk and insulated thereby from the casing, a metallic reflector fitted to said seat, and an electric light connected electrically to said reflector and an electric conductor adapted to contact with said metallic seat to supply current to the lamp. 70 75

3. In a flash light, the combination with a metallic casing, a disk of insulating material fitted in said casing and provided with an opening in the center thereof, a metallic member fitted in said opening and constituting a seat and a metallic reflector having its rear end engaging said seat. 80

4. In a flash light, the combination with a metallic casing, a disk of insulating material fitted in said casing and provided with an opening in the center thereof, a metallic member fitted in said opening and constituting a seat, a metallic reflector having its rear end engaging said seat and means engaging the forward end of the reflector for 90 maintaining the same in engagement with said seat.

5. In a flash light, the combination with a metallic casing, a disk of insulating material fitted in said casing, a metallic member 95 carried by the disk and insulated from the casing thereby, a lamp connected electrically to said metallic member and a circuit closer having an element movable to and from contacting position with said metallic member. 100

6. An article of manufacture comprising a circular disk of insulating material provided with an opening in the center thereof, a metallic reflector supporting ring surrounding said opening and spaced from the edge of the disk. 105

7. An article of manufacture comprising a circular disk of insulating material provided with an opening in the center thereof, a metallic reflector supporting ring surrounding said opening and spaced from the edge of the disk, said ring provided with means adapted to constitute the stationary element of a circuit closer. 110

Signed at New York city, in the county 115 of New York, and State of New York this 12th day of June, A. D. 1917.

JULIUS SAMACH.
